(57) **CLAIM**

The ornamental design for a sofa that converts into a bed, as shown in FIGS. 1-10, and described herein.

DESCRIPTION

FIG. 1 is a front perspective view of the sofa that converts into a bed, being in a sofa position;

FIG. 2 is a front view of the sofa that converts into a bed, being in a sofa position;

FIG. 3 is a back view of the sofa that converts into a bed, being in a sofa position;

FIG. 4 is a side view of the sofa that converts into a bed, being in a sofa position;

FIG. 5 is a side view of the sofa that converts into a bed, being in a sofa position;

FIG. 6 is a top view of the sofa that converts into a bed, being in a sofa position;

FIG. 7 is a bottom view of the sofa that converts into a bed, being in a sofa position;

FIG. 8 is a perspective view of the sofa that converts into a bed, with a split back rest, with the left section of the split back rest being in a bed position and the right section of the split back rest being in a sofa position;

FIG. 9 is a perspective view of the sofa that converts into a bed, being in a bed position; and,

FIG. 10 is a top view of the sofa that converts into a bed, being in a bed position.

The broken lines shown in the drawings are for illustrative purposes only and form no part of the claimed design.

1 Claim, 5 Drawing Sheets
